CLOTHES SUPPORTING ATTACHMENT FOR
IRONING BOARDS

Augusta F. Hipp, St. Joseph, Mo.

Application August 25, 1937, Serial No. 160,804

5 Claims. (Cl. 38—106)

This invention relates to improvements in a clothes supporting attachment for ironing boards, and has for its principal object, a clothes supporting attachment that is adjustable to support 5 clothes at different predetermined positions along the length of the board.

A further object of the present invention is the provision of a clothes supporting attachment that is adapted to be positioned in collapsed form 10 beneath the surface of the ironing board or extending therebeyond to support an apron suitable for receiving the clothes being ironed, whereby said clothes will be supported above the floor.

Other objects are simplicity and economy of 15 construction, efficiency of operation, and adaptability to the various forms of ironing boards.

With these, as well as other objects which will appear during the course of the specification, in view, reference will now be had to the drawing, wherein:

Figure 1 is a perspective view of an ironing board with a clothes supporting attachment associated therewith, embodying this invention.

Fig. 2 is an inverted plan view, with the clothes 25 supporting attachment shown in position thereon, some of the parts of which are broken away.

Fig. 3 is a fragmentary elevation of a portion 30 of the ironing board, with the clothes supporting attachment in position thereon.

Fig. 4 is a fragmentary, inverted plan of a portion 35 of the ironing board, showing the clothes supporting attachment in the collapsed position, and.

Fig. 5 is a sectional view, taken on line V—V 40 of Fig. 2.

Throughout the several views of the drawing, like reference characters refer to similar parts, and the numeral 10 designates an ironing board 45 of a common type wherein the board 12 is supported on legs 14. Many other types of supporting means might be used in the place of the one shown, since it is only essential that the board be supported by some means above the floor, for convenience of the operator.

The object of this invention is to provide a 45 clothes supporting means whereby the garments or other articles being ironed may be permitted to project below the board without any chance of becoming soiled by contacting the floor. This

supporting means 16 comprises a plate 18, which is securely attached to the underside of board 12 by means of screws 20. Sockets 22 and 24, integral with plate 18, are relatively offset and are positioned transversely of board 12 to re- 50 spectively receive right angled trunnions 26 and

28 of arms 30 and 32. The inner ends of arms 30 and 32 are respectively formed inwardly to produce trunnions 34 and 36, which rest respectively on tables 38 and 40 when the arms are extended toward the outer end of the board, as 5 show in solid lines. Tables 42 and 44 are provided at the other end of plate 18 to serve as bearing points of trunnions 34 and 36 respectively when the arms 30 and 32 are moved about their axes through one hundred eighty degrees 10 to extend inwardly, as shown in dotted lines in Fig. 2. Extension rods 46 and 48 are adapted to respectively telescope into hollow arms 30 and 32 and be adjusted therein to vary the total length of the arms. Trunnions 26 and 28 are 15 each provided at their outer extremities with cotter key 50, which serves to limit the outward movement of the trunnions.

Referring to Fig. 4, it will be noted that the arms 30 and 32 when moved inwardly, as shown, 20 fall entirely within the outer contour of the board for convenience of packing and to be out of the way when not in use.

The arms 30 and 32 are adapted to be extended beyond the opposite edges of the board to receive 25 an apron 52, which drops below and beneath the board to preclude any possible chance of the articles being ironed dropping to the floor.

Apron 52 is provided at its opposite edges with boots 54, through which the extension rods 46 30 are inserted, as shown in Fig. 1.

In the operation of the device, the arms 30 and 32 are first moved outwardly beyond the board 12. When so positioned, they may be independently rotated so as to extend toward the squared 35 end or the rounded end of the board. The extension rods 46 and 48 may be positioned to the desired distance beyond the arms 30 and 32, and the apron secured thereon. While it may appear that, when the arms are directed toward the 40 squared end of the board, there will be little room for the apron, however, it is sufficient to support articles being ironed on the board thereabove. In many instances this supporting attachment will be used on boards having but one central 45 leg and an end support, and in such cases, no interference will be experienced in the full use of the apron.

The convenient adjustment of the arms as a whole to and from a position beneath the board 50 and also from one end portion to the other end portion of the board, to support the apron in ar- cuate form therebelow, is very apparent, as de- scribed above.

What I claim is:

1. In combination with an ironing board having means whereby the board is supported above the floor; a pair of arms carried by said board and extending substantially parallel with the major axis thereof, adapted to be adjusted transversely to and from each other in a substantially horizontal plane and to and from a position directly beneath said board; and an apron carried by said arms to extend across and below said board.
- 5 2. In combination with an ironing board having means whereby the board is supported above the floor; a pair of arms pivotally carried by said board and abutment means to normally support said arms substantially parallel with the major axis thereof, adapted to be adjusted transversely in a substantially horizontal plane, to and from a position directly beneath said board; and an apron carried by said arms to extend across and below said board.
- 10 3. In combination with an ironing board having means whereby the board is supported above the floor; a pair of arms pivotally mounted in bearings carried by said board for rotation about a horizontal axis and abutting means at opposite sides of said bearings to selectively maintain said arms substantially parallel with the major axis thereof, said arms being adapted to be re-
- 15
- 20
- 25

spectively adjusted transversely in opposite directions in a substantially horizontal plane, to and from a position directly beneath said board; and an apron carried by said arms to extend below said board.

5

4. In an ironing board having means whereby the board is supported in operative position above the floor; a pair of rotatable arms carried by said board for rotation through substantially 180 degrees in vertical planes respectively, adjacent opposite longitudinal edges of said board and transversely movable in a substantially horizontal plane, to and from a position directly therebelow; and an apron carried by said arms adapted to present a clothes supporting trough 15 below said board.

10

5. In an ironing board having means whereby the board is supported in a raised, operating position above the floor; a pair of arms carried respectively adjacent opposite longitudinal edges 20 of said board for movement in substantially vertical planes, and transversely movable in a substantially horizontal plane to and from a position directly therebelow; and an apron supported at its opposite edges to said arms and extending 25 therebeneath intermediate said board and the floor.
